WEFT DETECTOR MECHANISM

Emil F. Arzt, Central Falls, R. I.

Application December 26, 1934, Serial No. 759,175

4 Claims. (Cl. 139—273)

This invention relates to a weft detector mechanism for looms, and more particularly to devices of this character adapted for closing an electric circuit when the weft supply in the shuttle becomes exhausted or substantially exhausted and thus bring into operation a suitable weft replenishing mechanism or stop mechanism operatively connected with the loom.

One object of the present invention is the provision of a simple and inexpensive device of this character which is positive in its operation, contains a relatively small number of movable parts, and which is capable of acting with certainty and precision to indicate the condition of the weft supply.

Another object of the invention is the provision of a device of this character comprising an angularly and longitudinally sliding weft detector member mounted for free bodily movement relative to a support and having simple but effective means for controlling its movements to insure its certainty of operation for setting in motion the necessary adjunctive devices upon the exhaustion or substantial exhaustion of the weft supply from a bobbin.

Other objects and advantages of the invention relate to various improved details of construction as well as certain novel combinations and arrangements of the parts as will be more fully set forth in the detailed description to follow.

Referring to the drawing: —

Fig. 1 is a top plan view of the detector mechanism, with the cover plate broken away, and illustrating in full lines the position of the parts when the weft detector member is making initial engagement with a full bobbin at the start of a detecting beat of the loom, while showing in dotted lines the position of the parts as the weft detector member is moved longitudinally of the support by continued advance of the lay beam.

Fig. 2 is a top plan view, similar to Fig. 1, but showing the position of the parts upon angular movement of the weft detector member resulting from a weft detecting beat of the loom after the filling has become exhausted or substantially exhausted.

Fig. 3 is a front elevational view of the detector mechanism, as seen looking towards the shuttles in Figs. 1 and 2, and,

Fig. 4 is a horizontal section view of a portion of the mechanism, taken along the line 4—4 of Fig. 3, and looking in the direction of the arrows shown in that figure.

In the embodiment of the invention illustrated herein, 1 designates a portion of a loom

frame having a bar 2 carried thereby upon which may be mounted a supporting frame 3, which may be secured to the bar in any one of a plurality of adjusted positions by means of a set screw 4.

The supporting frame 3 may be of any desired shape and appearance and is provided with a transverse guideway 6 having side walls 7 and end abutments 8 for suitably restraining and directing the movement of a weft detector member 9 mounted for both angular and longitudinal bodily sliding movement within said guideway. The bottom face 10 of the guideway may be an integral part of the support 3, while a cover member 11 may be secured to the supporting frame by screws or the like 12 and located in spaced relation with the bottom face 10 to serve as a top face for the guideway.

The weft detector member 9 comprises a straight portion 14 and an angular portion 15 to which may be secured a separate weft engaging plate 16, provided with edge corrugations 17, as by means of screws or the like 18. The weft engaging plate 16 may be formed of fibre, bakelite or other similar material, although it may be made integral with the weft detector member 9 if desired. That portion of the weft detector member 9 which is normally positioned within the guideway 6 is provided with lateral lobate arms 20, each of which is rounded, as shown in Figs. 1 and 2 of the drawing, to slidably engage the side walls 7 of the guideway and permit either angular or longitudinal sliding movement of the weft detector member relative to the support. A pair of pins 21 may extend upwardly from the bottom face 10 of the guideway, and are so positioned as to be in substantial engagement with the lateral arms 20 at points adjacent to the termination of the rounded edge portions when the rounded edges of the lobate arms 20 contact with the end abutments 8 and thereby serve as hinge points about which the weft detector member may turn in any angular sliding movement of the weft detector member relative to the support, without permitting the end of one of the lobate arms to bind against one of the side walls 7 in making the turning movement.

A contact plate 24 is carried by the weft detector member 9 and may be formed integral therewith or secured thereto by any suitable means, such as screws 25. The plate 24 is provided with an extension 26 normally positioned within a transverse opening 27 formed in the supporting frame. The extension member 26 is adapted to engage an electric contact member 28 carried by an insulating block 30 which is secured to the

supporting frame by any suitable means, such as a screw 32, upon angular sliding movement of the weft detector member 9, as shown in Fig. 2 of the drawing.

5 A stud 34 carried by the weft detector member 9 is connected with one end of a coiled spring 36, the opposite end of the spring being anchored to a stud 37 carried by the supporting frame. The coiled spring 36 serves to maintain the weft detector member 9 normally in extended position for engagement with a bobbin upon each weft detecting beat of the loom.

10 The electric contact member 28 forms part of an electric circuit which includes the wire 39 and contact supporting bolt 33, and which circuit is adapted to control a suitable weft replenishing mechanism or a stop device, as the case may be after a manner well known in this art. The engagement of the extension member 26 with the 15 contact member 28 serves to close the electric circuit through the machine frame to actuate such mechanism after a manner well known in devices 20 of this character.

15 A loom shuttle 40, provided with a bobbin 41 carrying a weft filling 42, is shown in Fig. 1 of the drawing, with the weft detector member 9, as shown in full lines, located in position to pass the weft engaging plate 16 through the usual feeler opening 43 in the shuttle and into contact with 20 the weft filling at the beginning of the detecting beat of the loom. The presence of a substantial quantity of weft filling upon the bobbin 41 when engaged by the plate 16 prevents slippage of the plate member longitudinally of the bobbin and results in longitudinal sliding movement of the weft 25 detector member transversely of the supporting frame 3, as shown in dotted lines in Fig. 1, as the shuttle 40 and bobbin 41 move forwardly on the detecting beat. As the weft detector member is 30 held against substantial angular movement relative to the supporting frame 3, the extension member 26 of the plate 24 fails to engage the electric contact member 28 and the lay beam moves back out of the way of the weft detector member 35 without closing the electric circuit to indicate replenishment or actuate a stop mechanism.

35 In Fig. 2 of the drawing, the loom shuttle body and bobbin 41 are shown moving forwardly on a detecting beat of the loom when the weft filling 42 has reached a state of substantial exhaustion. In such a case the plate member 16 upon engagement with the spindle, or a sparse winding of weft filling, is not restrained from angular movement by the presence of the filling and moves 50 towards the left, as shown in that figure, by reason of the angularity of the portion 15 of the weft detector member. This results in imparting a bodily sliding movement to the weft detector member 9 in which the lobate arm 20 located at 55 the right of that figure initially turns about the pin 21 located adjacent thereto to swing about the pin 21 in a direction angularly of the supporting frame and bring the extension member 26 into engagement with the electric contact plate 28 to 60 close the electric circuit through the machine frame and either indicate replenishment or actuate a stop mechanism.

65 The supporting frame 3, bar 2, loom frame 1 and the main portion of the weft detector member 9 may be of any suitable metal construction, and being in continual contact serve as a ground for completing the electric circuit when the extension member 26 engages the electric contact plate 28 upon angular sliding movement of the weft detector member.

70 The supporting frame 3, including the cover plate 11, as well as the detector member 9, may be formed from iron, steel, bronze or the like, such as is well adapted to serve as a conductor of an electric current, and if desired, the side walls 7 5 of the recess as well as the lobate arms 20 may be hardened to reduce wear.

75 It will be seen that the present construction is of an exceedingly simple character comprising few parts so arranged as not to get out of order 10 readily and requiring little or no change or adjustment when in use. The device is positive in its operation, as the engagement of the corrugated edge 17 of the plate 16 with the weft material insures substantially straight line longitudinal 15 movement of the weft detector member when a substantial amount of filling is carried by the bobbin, and the rounded lobate arms 20 engaging the side walls 7 insure free sliding movement of the weft detector member longitudinally as well 20 as the unhampered return of the weft detector member to its initial position under the influence of the coiled spring 36. The provision of the hinge members 24 suitably located with respect to the rounded end portions of the lobate arms 20 25 insure the desired angular movement of the weft detector member for closing the electric circuit upon exhaustion or substantial exhaustion of the weft filling without danger of the weft detector member becoming jammed or cramped in its 30 movement relative to the supporting frame.

35 What I claim is:

1. In a weft detector mechanism for looms comprising a fixed support provided with opposed walls forming a transverse guideway having laterally reduced and laterally enlarged portions, a weft detector member having a longitudinally extending portion of less width than the reduced portion of said guideway slidably mounted in said guideway for angular and longitudinal sliding 40 movement relative to said support and provided with oppositely positioned arms extending outwardly from the longitudinally extending portion thereof within the laterally enlarged portion of said guideway, spring means connecting said support and detector member for exerting tension upon said detector member in a direction substantially along the central longitudinal line of the longitudinal portion thereof, an insulated electric contact member, and contact means carried by said weft detector member and movable into engagement with the electric contact member to close an electric circuit upon angular sliding movement of said weft detector member in one direction relative to said support. 50

55 2. In a weft detector mechanism for looms, a fixed support provided with side and end walls forming a guideway having a widened portion and a narrowed end portion located substantially medially of the widened portion, an elongated weft detector member mounted in the guideway for free angular and longitudinal sliding movement in any direction in the plane of the weft detector member and within the limits of the guideway and provided with outwardly projecting side portions engageable with the side or end wall portions of said guideway for controlling the sliding movement of said weft detector member, spring means connecting said support and weft detector member normally urging both of the outwardly projecting side portions of the weft detector member into contact with respective end walls of the guideway, and means actuatable upon angular movement of said weft detector member in 60 65 70 75 80 85 90 95 98 99 100 101 102 103 104 105 106 107 108 109 110 111 112 113 114 115 116 117 118 one direction for effecting a change in the operation of the loom.

3. In a weft detector member for looms, a fixed support provided with side and end wall portions 5 forming a guideway having a transversely widened portion and a narrowed end portion located substantially medially of the widened portion, an elongated weft detector member slidably and non-pivottally mounted in said guideway for free bodily 10 sliding movement in any direction in the plane of the detector member and within the limits of the guideway and provided with an intermediate portion of greater width than one end portion for engagement with the side and end wall portions 15 of the guideway for limiting the extent of angular and longitudinal sliding movement of said member within the guideway, an electric contact member carried by but insulated from said support, contact means carried by said weft detector 20 member and maintained out of engagement with said electric contact member upon longitudinal sliding movement of said weft detector member relative to said support but engageable with said electric contact member upon angular sliding 25 movement of said weft detector member in one direction relative to said support, and spring means connecting said support and weft detector member.

4. In a weft detector mechanism for looms, a

fixed support having a face portion and provided with side and end wall portions angularly positioned relative to said face portion and forming a guideway having a widened portion and a narrowed end portion located substantially medially of the widened portion, an elongated weft detector member having a longitudinally extending portion of materially less width than the widened portion of the guideway and mounted upon the face portion thereof for free sliding movement longitudinally of its extent and angularly thereof in any direction within the limits of the guideway, oppositely positioned means carried by said weft detector member and engageable with the side and end wall portions of the guideway for limiting the longitudinal and angular movement thereof, spring means connecting said support and weft detector member and effective upon the weft detector member to impart thereto a substantially straight line movement longitudinally 20 of said detector member and transversely of said support, an electric contact member carried by but insulated from said support, and contact means carried by said weft detector member and movable into engagement with said electric contact member upon angular movement of said weft detector member in one direction relative to said support. 25
